UNITED STATES PATENT OFFICE.

JOHN C. SCOVEL, JR., OF CHICAGO, ILLINOIS, ASSIGNOR TO THE CREAMERY PACKAGE MFG. COMPANY, OF CHICAGO, ILLINOIS, A CORPORATION OF ILLINOIS.

REFRIGERATING APPARATUS.

Application filed October 4, 1922. Serial No. 592,263.

To all whom it may concern:

Be it known that I, JOHN C. SCOVEL, Jr., a citizen of the United States, residing at Chicago, in the county of Cook and the State of Illinois, have invented certain new and useful Improvements in Refrigerating Apparatus, of which the following is a specification.

The invention relates to refrigerating apparatus, more particularly to the refrigerant condensing means employed in such apparatus.

In the smaller units of refrigerating apparatus, designed for use in domestic or small commercial installations, compactness of arrangement and a minimum of space necessary to accommodate the apparatus are important features. Certain minimum areas of radiating surface are necessary in the commonly used water-cooled conduits where condensation of the returned refrigerant gas is effected after compression. As heretofore arranged such condensers are bulky and require a considerable space in the installation of the apparatus.

One of the objects of this invention is to provide a condenser of extremely compact construction, in which the heat extracting efficiency of the cooling medium is largely increased with a decrease in the space commonly required for the accommodation of the cooling coils.

Another object is to provide an arrangement of water-cooled condenser piping in which a materially shortened length of conduit may be employed without sacrifice of cooling surface area.

A further object is to provide a simple, durable and inexpensive condenser construction which may be housed in a unitary structure adapted also to accommodate the cooling medium about the compression cylinders.

Other objects and advantages will be apparent in the following detailed description of a preferred embodiment of my invention which I have chosen for illustration in the accompanying drawings.

In the drawings, Fig. 1 represents an end elevation of a refrigerating machine employing the features of the invention. Fig. 2 is a plan view of the machine with the upper portion of the condenser housing or casing removed. Fig. 3 is a longitudinal sectional elevation of the machine. Fig. 4 is a cross sectional elevation of the compression

cylinders, condenser and casing. Figs. 5 and 6 are respectively a vertical sectional view and top view of the condenser unit. Fig. 7 is a sectional detail of the base and liquid receiver construction with connections. 60

Referring to the drawings, the reference numeral 1 indicates a shell base structure upon which the compressor is mounted, and which may support also an electric motor 2 for driving the apparatus. As illustrated 65 herein, the compressor unit comprises a closed crank case 3 in which is suitably journaled a crank shaft 4 carrying a driving pulley 5, the latter in the present instance receiving power through a belt 6 from the 70 motor 2.

Mounted on the crank case and preferably integral therewith are one or more compression cylinders opening into the crank case, two being shown herein at 7. The cylinders 7 are adapted to accommodate suitable pistons (not shown), of the type carrying inlet valves to receive a gas charge from the crank case, and operatively connected to the crank shaft 4. The enlarged upper portions of the cylinders as shown are adapted to accommodate discharge valve heads (not shown) of any suitable type, the compressed gas being discharged therefrom through the 75 passages 8 to the condenser coils. Low pressure gas returning from the refrigerating coils is conducted through the pipe 9, scale trap 10, and passage 11 formed in the crank case and cylinder structure, to the interior 80 of the sealed crank case.

A sectional casing 12, carried by the crank case and with its lower portion preferably integral therewith, entirely encloses the cylinders 7 and provides also a substantial chamber thereabout. Housed within the 85 casing 12 is a condenser of double tubing comprising an outer tube 13 and a spaced inner tube 14 forming between them an annular passage 15. The condenser tubing is coiled about the cylinders within the casing 100 chamber in compact arrangement minimizing the space necessary for its accommodation, and preferably terminating respectively at the top and bottom of the chamber, the ends of the outer tube 13 being suitably closed and sealed to the inner tube 14.

A tubular connection 16 leads from the junction of the discharge passages 8 and 105 communicates through the wall of the tube 13, preferably adjacent its upper end, with 110

the annular passage 15. Another connection 17 opening into the lower end of the tube 13 leads through the wall of the casing and a suitable control valve 18 to a liquid receiver 19 preferably positioned within the base structure 1.

5 A valve controlled liquid line 20 conducts the condensed refrigerant from the receiver 19 to the refrigerating coils (not shown).

10 A charging connection 20 permits the renewal of the charge of refrigerant when required. A further connection 22 opening from the upper portion of the tube 13 leads through the casing 12 to a pressure gage 23.

15 A valved oil drain 24 provides an outlet for the crank case when desired.

The condenser cooling medium, preferably water, enters through the lower portion of the casing by the pipe 25, the latter being a 20 continuation of the inner condenser tube 14. After coursing within the inner tube through the condenser, the water is discharged into the casing chamber from the open upper end 26 of the tube 14, filling the chamber and 25 submerging the outer condenser tube 13. The water in the chamber also submerges and cools the compression cylinders 7. A discharge outlet 27 provides for the outflow of the warmed water from the casing.

30 In operation, the compressed refrigerant gas being discharged from the cylinders flows through the annular passage 15 in the condenser on its way to the receiver 19. The form of the passage creates an annular 35 stream of gas of thin cross section which is in contact both inwardly and outwardly with the water cooled walls of the tubes 14 and 13. It will be obvious that my arrangement of both inner and outer cooling 40 walls greatly facilitates the absorption of the heat from the flowing gas and materially hastens its liquefaction.

The increased efficiency obtained by both 45 submerging the condenser and providing an inner cooling coil therein, permits a large reduction in the dimensions of the condenser coils from that otherwise necessary to effect the cooling and liquefaction of the compressed gas, the combined effective cooling 50 surface of the inner and outer condenser coils being approximately twice that of a single submerged tube or of a double tube cooled internally only.

Also, by my arrangement of the submerging 55 chamber about the compression cylinders, the water bath effects the cooling of the cylinders without other provision of water jackets thereabout. The reduced dimensions of the condenser coils permits this 60 arrangement within practicable dimensional limits of the compressor unit, and accomplishes extreme compactness in the apparatus as a whole.

It will now be apparent that I have pro-

vided a simple, durable and inexpensive construction which effectively accomplishes the purpose set forth herein.

I claim as my invention:

1. In apparatus of the class described, the combination with fluid compressing means 70 of a casing forming an enclosed chamber about said compressing means, and a double tubular conduit in said casing comprising an outer tube enclosing a spaced inner tube and forming a passage therebetween, said 75 passage being connected with said compressing means to receive compressed fluid for condensation and having an outlet therefor, said inner tube having connection with a supply of cooling liquid and discharging 80 same into said chamber, thereby submerging said conduit and said compressing means.

2. In apparatus of the class described, the combination of a fluid compressor cylinder, a casing substantially enclosing said cylinder and adapted to contain cooling liquid for the submersion of said cylinder, a coiled double tube in said casing positioned for submersion in said cooling liquid and comprising an inner tube having one 90 end connected with a supply of cooling liquid exterior to said casing and having its other end open for the discharge of said liquid into said casing, and an outer tube enclosing said inner tube in spaced relation 95 to form a passage therebetween, the ends of said outer tube being sealed upon said inner tube, a connection for the flow of compressed fluid from said compressor cylinder to said passage, and an outlet connection from said 100 passage for the discharge of condensed fluid.

3. In refrigerating apparatus, a combined compressor and condenser unit comprising a pair of compression cylinders, a closed crank case supporting said cylinders and communicating therewith, a sectional casing having a base portion supported on said crank case and having a removable cover portion, said casing enclosing a chamber about said cylinders, a refrigerant inlet passage formed in the base of said casing opening into said crank case, and a double tubular condenser in said chamber having an annular refrigerant passage and an inner cooling medium passage, said refrigerant 110 passage having connection with said cylinders to receive compressed refrigerant therefrom and having a refrigerant outlet connection through a wall of said casing, and said inner passage having a water supply connection through a wall of said casing whereby water may flow through said inner passage and be discharged therefrom to fill said chamber and submerge said cylinders 115 and said condenser.

In witness whereof I have hereunto set my hand.

JOHN C. SCOVEL, JR.
